UNITED STATES PATENT OFFICE.

CHARLES WOEHRLE, OF NEW YORK, N. Y.

DESIGN FOR A DRIP-PAN.

SPECIFICATION forming part of Design No. 15,570, dated November 18, 1884.

Application filed September 3, 1884. Term of patent 14 years.

To all whom it may concern:

Be it known that I, CHARLES WOEHRLE, a citizen of the United States, residing at New York, in the county of New York and State of New York, have invented and produced a new and original Design for Drip-Pans, of which the following is a specification, reference being had to the accompanying drawings.

My design relates to drip-pans; and it consists of the novel features hereinafter described, and illustrated in the accompanying drawings, in which—

Figure 1 is a front view, and Fig. 2 is an end view.

Similar letters indicate similar parts.

The letter A designates the back of the pan, C the bottom, and D the ends, thereof. The back A is straight, while the bottom C is round and forms a continuation of the back,

it terminating at a point below the top of the back, where the latter is ornamented with buttons e. The ends D correspond in outline on one edge to the back and bottom, and the forward portions thereof are curved in a direction inward to the pan, as shown in Fig. 2.

What I claim is—

The design for a drip-pan, herein shown and described, the same consisting of the straight back, the round bottom, and the ends corresponding in outline on one edge to the back and bottom, and having the forward portions curved inwardly to the pan.

In testimony whereof I affix my signature in presence of two witnesses.

CHARLES WOEHRLE.

Witnesses:

CHAS. WAHLERS,
FRANCIS C. BOWEN.
